UNITED STATES PATENT OFFICE

EVANGEL A. HAVELES, OF LOS ANGELES, CALIFORNIA

RESTAURANT CHECK HOLDER AND PUNCHING DEVICE

Application filed December 28, 1929. Serial No. 417,230.

My present invention relates to holders and punching devices for checks, such as used in restaurants, and more particularly to such holders and devices adapted to be used in connection with table service in restaurants so that the same may be readily handled or carried around by the waiters.

The objects of my present invention are: First, to provide a device of this class for holding a number of checks in the form of a pad and one into which the pad may be easily positioned and from which it may be easily removed for placing other pads therein; second, to provide a holder of this class which is provided with novel and simple punching or perforating means so that the individual checks of the pad may be easily and variously punched or perforated; third, to provide very compact punching means in connection with a holder of this class whereby the punching means will not interfere in any way with the carrying of the device from place to place, in the pocket, or the like; fourth, to provide novel means in connection with a device of this class for directing and placing the check into the punching means preparatory to punching the same, and also novelly arranged punching means so that the number or character to be punched, or indicated on the check, may be readily determined, that is, an arrangement whereby the perforations may be readily made opposite the desired number or character, or other designation; and fifth, to provide as a whole a novelly constructed device of this class and one which is simple and economical of construction, durable, and which will not readily deteriorate or get out of order.

With these and other objects in view, as will appear hereinafter, my invention consists of certain novel features of construction, combination and arrangement of parts and portions, as will be hereinafter more particularly described in detail and set forth in the appended claims, reference being had to the accompanying drawings and to the characters of reference thereon, which form a part of this application in which:

Figure 1 is a perspective view of my check

holding and punching device in one form of construction, showing the punching means in a punching position and showing the same with the pad of checks removed; Fig. 2 is a side elevational view thereof, taken from the side opposite the punching means, showing by dotted lines one of the checks in position to be punched; Fig. 3 is an elevational view taken from the opposite side, and showing by dotted lines the punching means in a seated or normally open position; Fig. 4 is an end view thereof, showing the punching means in open position; Fig. 5 is a top view on a reduced scale of one form of checks adapted to be used in my device; Fig. 6 is a fragmentary view in plan of my device in a slightly modified form of construction; Fig. 7 is an end view thereof; Fig. 8 is a fragmentary elevational view thereof taken at 8-8 of Fig. 6; and, Fig. 9 is a fragmentary sectional elevational view thereof taken through 9-9 of Fig. 6.

Like characters of reference refer to similar parts and portions throughout the views of the drawings.

My device, as shown in Figs. 1, 2, 3 and 4, consists essentially of a back plate 1, a pad holding member 2, a punching member 3, a pivot member 4, and a spring 5.

The back plate 1 forms the main supporting member of my device. It is preferably formed as a channel, the bottom of which extends over the back side of the pad and the side flanges, designated 1a, enclosing a portion of the side edges of the checks of the pad. At or near one end of the member 1 is positioned the holding member 2. This member 2 is preferably made of resilient metal of U-shaped cross section and is secured in any suitable manner with one flange to the bottom of the member 1. The holding member 2 extends transversely across the one end of the member 1 and is adapted to receive between the flanges thereof the head end of a pad of checks, that is, the end thereof at which the ends of the checks are fastened together.

The portion 1b forming the bottom of the member 1 is preferably extended beyond the ends of the flanges 1a and beyond the hold-

ing member 2, and is preferably offset downwardly or backwardly forming a ledge 1c which extends the greater distance across the head end of the device but spaced from the side of the device provided with the punching means. At such side of the member 1 the portion 1b is extended straight back without being offset and also beyond the side of the member 1, as shown in Figs. 1 and 4, said extended portion, designated 1d, serving as the die for the punching means. The punch in this instance consists of a lever 3 which is pivotally mounted intermediate its ends against the outer side of one of the flanges 1a of the member 1 by the pivot member 4 which in this instance is a rivet. Between the outer head of the rivet and the outer side of the lever 3 and around the shank of the rivet is a spacer 6 which retains the lever 3 against the member 1. Around the spacer 6, which is circular in form, is mounted the coil spring 5 the ends of which extend through the sides of the rivet, one end being secured in the lever 3 and the other in the adjacent flange 1a of the member 1. The spring is so arranged that the punching end 3a of the lever is normally forced from the die portion 1d of the member 1, as shown by dotted lines in Fig. 3. The action of the spring is limited by a stop 3b between the pivotal portion of the lever and the punching end thereof, which stop is adapted to engage the upper edge of the flange 1a. The punching end of the lever 3 is provided with a bent portion which extends toward the die portion 1d and which is provided at the turned portion with an inclined shearing punch 3c which is adapted to extend through a correspondingly shaped opening 1e in the die portion 1d, as shown in Figs. 1, 2 and 3, for punching holes in the checks 11, shown in Fig. 5, which holes are designated 11a. The angular construction of the punching portion 3c facilitates the punching operation and, when the lever is in the dotted line position, serves as a guide to facilitate the introduction of the edge of a check between the punch and the die. It will be noted that the check is preferably laid with one edge on the ledge 1c which edge is also placed between the punch and die portion.

The opposite end of the lever 3 is provided with a flattened outwardly bent portion 3d whereby the operation of depressing the lever is facilitated. It will be noted that whether the lever is free, as shown by dotted lines, or depressed, as shown by solid lines, the whole structure is very compact and can be very readily placed in the pocket.

The checks, when secured together in the form of a pad, may be fastened together by a staple 12 at the middle portion of one end. This staple, when projecting slightly above the upper side of the pad, serves as an ef-

ficient lock when the pad is in position, such portion of the staple extending to an elongated slot 2b in the holding member 2.

If desired, there may be provided at one side of the back plate member 1 a resilient pencil holding clip 21 so that the pencil will be held in connection with the pad at all times ready for use.

In the modification shown in Figs. 6, 7, 8 and 9, the holding means for the pad of checks is substantially the same as that previously described, but the punching means here consists of a plunger instead of a lever as in the other construction. In the structure shown in Figs. 6, 7, 8 and 9, the supporting and guiding ledge 1c for the edge of the check preparatory to punching or perforating the same extends preferably completely across the head end of the back plate 1 and may be made slightly wider. In this ledge, at the punching side of the device is also a die portion into which is adapted to extend from the front or upper side of the ledge a plunger 31. This plunger is reciprocally mounted in a frame 32 which is provided at its inner end with an angular portion 32a for securing the frame by rivets 33 and 34 to the side flange 1a and the bottom of the back plate. The portion extending outwardly from the securing portion consists of a bottom plate portion 32b and an upper plate portion 32c between and in which the plunger 31 is reciprocally mounted. Around the plunger and between said plate portions is positioned a compression spring 35 which is adapted to be compressed by a pin 36 extending through the plunger and normally engaging the inner side of the upper plate portion. The bottom and top plate portions 32b and 32c are preferably partially enclosed by bending a portion of the frame around the plunger and spring between the plate portions, as shown in Figs. 6, 7, 8 and 9. The ledge 1c and the lower plate portion 32b are preferably bent outwardly from each other forming a guide to facilitate the introduction of the edge of the check therebetween preparatory to punching the same.

In the ledges 1c may be provided a hole 1f so that the device may be supported or located on a nail, or the like.

Though I have shown and described a particular construction, combination and arrangement of parts and portions, and a certain modification thereof, I do not wish to be limited to this particular construction, combination and arrangement, nor to the modification, but desire to include in the scope of my invention the construction, combination and arrangement substantially as set forth in the appended claims:

Having thus described my invention, what I claim as new and desire to secure by Letters Patent is:

1. In a device of the class described, a check holder comprising a back plate provided at one side with an upwardly extending flange and at one end with a die portion in substantially the plane of the back plate and substantially in alignment with the flange, a punching lever pivotally mounted intermediate its ends on said flange and provided at its forward end with a punching portion adapted to engage the die portion, and a spring normally separating the punching portion from the die portion.
- 10 2. In a device of the class described, a check holder comprising a back plate provided at one side with an upwardly extending flange and at one end with a die portion in substantially the plane of the back plate and substantially in alignment with the flange, a punching lever pivotally mounted intermediate its ends on said flange and provided at its forward end with a punching portion adapted to engage the die portion, and a spring normally separating the punching portion from the die portion,
- 20 25 30 the punching portion being inclined outwardly and away from the die portion in a manner to facilitate the introduction of a check between the die portion and the punching portion.

In testimony whereof, I have hereunto set my hand at Los Angeles, California, this 21st day of January 1929.
